DESIGN FOR A WIRE STITCHING MACHINE

William O. Sims and Edward J. Rodda, Niagara Falls, N. Y., assignors to Niagara Falls Wire Stitchers, Inc., Niagara Falls, N. Y., a corporation of New York

Application April 12, 1937, Serial No. 68,699

Term of patent 14 years

To all whom it may concern:

Be it known, that we, William O. Sims and Edward J. Rodda, citizens of the United States, residing at Niagara Falls, in the county of Niagara, State of New York, have invented a new, original, and ornamental Design for Wire Stitching Machines, of which the following is a specification, reference being had to the accompanying drawing, forming part thereof.

Figure 1 is a front elevation of a wire stitching machine, showing our new design.

Fig. 2 is a horizontal section of the same taken on line 2—2, Figure 1 and looking downwardly.

Fig. 3 is a perspective view of the same.

We claim:

The ornamental design for a wire stitching machine, as shown.

WILLIAM O. SIMS.
EDWARD J. RODDA.
